WALL CONSTRUCTION

Alvin C. Goddard, Forest Hills, and Raymond P.
Le Viness, Queens Village, N. Y.

Application September 23, 1932, Serial No. 635,166

13 Claims. (Cl. 139—34)

This invention relates to wall construction and particularly to that species of structure which is of a removable and temporary character and is mainly used to subdivide larger compartments of 5 permanent stationary confines, such as business offices, waiting rooms, halls and the like. Structures of this character, commonly called "partition walls" are advantageously made of parts more or less standardized and interchangeable, 10 which may be readily installed or removed.

While that general construction which is rather common and basic to all previous constructions of this kind known in the art, has been followed, the invention has for its specific purpose the 15 improvement of the means for attaching the standardized or interchangeable parts to each other.

Our invention has for its prime object the provision of a simplified system of unit parts, which, while interchangeable, satisfies the 20 differing conditions met with in the subdivision of rooms.

Another concurrent object is to provide vertical partitions made up of interchangeable vertical 25 panel units comprising either a single vertical panel member or a plurality of panels arranged one above the other.

A third object is to construct the units of as few component parts as possible in order to simplify their erection and to facilitate manufacture. 30

A fourth object is to provide simple means whereby the parts may be rigidly and securely installed by unskilled workmen with the use of ordinary tools.

A fifth object is to make the attaching means of 35 a standard uniform nature so that they may be employed with little or no change in a straight series of units or at intersections of straight walls, corner construction, and where doors and windows must be provided.

A sixth object is to provide for the installation of windows and transom panels by similar simple attaching means as are used for the combination of unit panels.

A seventh object is to provide cornice members and means for attaching them to the tops of the 40 panel units.

An eighth object is to so shape the component unit parts, including the cornice members, that 45 filler pieces may be inserted in the simplest and most efficient manner wherever space, aside or above the units, is too narrow for a standard unit.

A ninth object is to provide means to fasten the various units securely to the floor and provide 50 equalizing means to compensate for any uneven-

ness of the floor so that the panel units may be aligned with each other irrespective of such unevenness.

A final object, subservient to all the objects aforesaid, is to make all unit parts of a simple, 5 rigid, inexpensive and esthetically pleasing construction.

Other objects and advantages will be apparent from the detailed description of parts hereinafter and illustrated by the accompanying drawings, 10 in which:

Fig. 1 is a front elevation of a partition wall according to our invention, made up of three units, the two outer units comprising two large panels, the upper one being glazed, and a transom member, while the intermediate unit represents a door having a glass panel and a transom light over the door. Across all three units a cornice runs and above the cornice and alongside the ends of the outer units a space is shown which is occupied by filler pieces to cover the remaining area between the partition wall and the building walls and ceiling, both indicated by section lining; 15

Figs. 2 to 7 inclusively show horizontal sections through different units, and specifically:

Fig. 2 shows an intersection or abutment of two partition walls with each other at right angles, the lower continuous wall showing a door hinged near a corner and the abutting wall showing a 20 filler panel, a single connector element and a panel with a window inserted, counting from the top of the view downwardly in the order named, certain panel portions being broken away to reduce the extent of the figure;

Fig. 3 is a fragmentary section showing a similar abutment applicable when no door is near the corner where the two walls abut or intersect;

Fig. 4 shows one possible construction of a plain corner;

Fig. 5 shows another corner construction;

Fig. 6 shows a modification of the metal connector construction shown throughout the former sectional views;

Fig. 7 is similar to Fig. 6 except that it shows the application of the invention to units made of other material than metal, such as wood, composition or the like;

Fig. 8 is a vertical section through a panel unit similar to those shown in Fig. 1, but without the transom, the cornice being placed directly above 50 the glazed panel portion, intermediate portions of the panels being broken away and omitted to reduce the height of the figure. The upright is here indicated in outline.

Fig. 9 is a vertical section through the window 55

rail along line 9—9 of Fig. 1, and if this figure were inserted in the section shown in Fig. 8, the latter would indicate a complete section through one of the outer units of Fig. 1;

5 Fig. 10 shows a vertical section through a door panel with a cornice member attached directly above the door casing;

Fig. 11 shows the connection of the top of the door casing with a transom light similar to the one shown in the middle unit of Fig. 1;

10 Fig. 12 represents a vertical section through the upper portion of a glazed panel unit, the space between the cornice and the ceiling being filled by a double wall of composition boards or other 15 suitable material;

Fig. 13 is a partial plan view looking down into the bottom of the cornice member and illustrating the bracing of said member and the means whereby it is connected to the panel units;

20 Fig. 14 is a vertical middle section through the cornice member and part of a connector element, showing the tie-rod connecting two of the cornice bracing spacers;

Fig. 15 is a perspective view of an interconnecting strut seated in one socket provided on a connector member;

Fig. 16 is a diagrammatic elevation of the post member indicating the location of the sockets;

Fig. 17 is a top plan view of a connector base 30 plate;

Fig. 18 is a front elevation of said base plate showing a fractional part of the upright connector members;

Fig. 19 is a section along the line 19—19 of 35 Fig. 17.

Fig. 20 is a vertical section through a panel unit of wood or composite material, illustrating how the cornice may be fastened to the ceiling and the top of the panel units by similar means 40 as are employed to connect the panel units to each other;

Fig. 21 shows a horizontal section through the adjacent vertical edges of two units made of wood or composite material, the pilaster plates being 45 slightly modified and the space between the coupled edges of the units filled with sound deadening material;

Fig. 22 is a perspective view of a simplified form of a panel base between two adjoining wooden 50 units, in the shape of a fishplate, screwed to the floor and tying the base channels of the adjoining units together;

Fig. 23 is a diagrammatical representation of a partition wall showing the system of interconnecting struts tying the single units to each other and to the ceiling in the manner detailed in Fig. 20. It also shows a modification of providing 55 seats for the interconnecting struts, adapted especially for wooden or composite material, and

60 Fig. 24 is an end view of one of the units shown in Fig. 23.

Similar characters are used to designate similar parts throughout the different views.

Referring more in detail to the separate views, 65 Fig. 1 comprises a complete partition installation made up of three units, 21, 22 and 23, two upright filler members 24 and 25, and a cornice 26 common to the unit sections and the filler members. The clearance between the cornice and the ceiling 70 may be left free or may be occupied with a horizontal filler member 27, as desired. The unit sections are standardized in dimensions and construction. Preferably the horizontal and vertical dimensions of all units are identical, but the dimensions of the vertical and horizontal filler 75

members will be determined by the exigencies of each particular job.

The main parts upholding the partition and forming the supporting frame for the panel members consist of the vertical uprights or connector strips 30 at the junction of adjacent units, extending from the floor 31 to the cornice 26 as illustrated in Fig. 8 and the sectional views of Figs. 2 to 7. These connector strips are provided in pairs 30, 30 and consist substantially of a flat vertical web portion 30' flanked by two deep-grooved channel portions 30'', 30''. Each pair of connector strips face each other with their open channels and are interconnected in spaced apart relationship by a suitable number of diagonal struts 32 seated in sockets 33 provided on the web portions. These sockets are formed, as indicated in Figs. 15 and 16, by molding semi-circular grooves 34, 34, parallel to each other and suitably spaced apart in a longitudinal vertical 10 direction in the web, and slicing out and retroverting short lengths 35 of these grooves, so that they form loops bent in the opposite direction from said grooves, thus cooperating with the outwardly bent grooves to form substantially circular 15 sockets for the reception of the free ends of the U-shaped struts 32. The ends of the struts are preferably of different lengths, the longer end 32' being first partly inserted into a socket, whereupon the short end is swung around over the diametrically opposite socket of the opposite upright and both are driven into their sockets to form a rigid bracing between the uprights. The 20 grooves 34 may run throughout the whole length of the upright, adding thereby to its compressive 25 strength and rigidity, or they may be formed intermittently where required to form a socket.

It is to be noted that besides increasing the vertical stiffness of the connector strips 30 the longitudinal flutings or grooves 34 serve a double 40 function in that they provide the material from which the short lengths 35 may be struck out without stretching the metal and they also provide together with the inner walls of the channels 30'' seats for the side plate filler members 49 as 45 is shown at 49a, Fig. 2.

A modified way of providing sockets for the interconnecting struts consists in fastening short plates 101 (Figs. 23 and 24) instead of continuous 50 uprights to the opposite ends of the panel units at suitable intervals. This method is especially applicable to walls made of wood or composite material, as illustrated. The struts used in connection with these plates are the same as those above described and the plates are provided with 55 similar sockets, but the plates may be flat and are fastened with screws 102 to the partition edges.

To close the space between the connector strips of each pair and conceal the bracing 32, cover plates or pilasters 36 (Figs. 2—5) are provided, 60 removably mounted and secured in place as will now be described. These plates are substantially channel-shaped in cross-section, and the web part may be of any desired ornamental form, 65 preferably with longitudinally running folds or bends 37 in it to lend it rigidity, but the channel legs 38 are made resilient by having an S-shaped cross-section. These S-shaped legs are sprung 70 over the channel ends 30'' in the manner shown and thus coat with the latter to close the space between the panel units. For purposes of shipment, these parts are not assembled, but if desired, each unit section with its connector strips 75

30 may be assembled at the factory and shipped in assembled relationship.

5 Figs. 6 and 7 show a modification of the way the pilasters may be attached to the panel units. Instead of springing the resilient legs of the pilaster members between the inside ends of the channels 30", they are clamped over the projecting grooved ends 39 of the connector strips from the outside, as shown. The interlocking resilient flanges of both the connector strips and the cover plates are correspondingly modified.

10 If desirable the hollow interior of the partition units as well as the hollow connecting elements between them may be filled with sound deadening material. If the panels are made of solid wood or other sound absorbing material, then the hollow spaces between panels may be filled as shown in Fig. 21. This also shows how the connector strips 30 in this case are fastened by screws 103 upon the partition edges. The pilaster plates 104 which have a simple box-like shape in this modification are fastened on the extant wings 105 of the connector strips in the manner previously described.

15 As shown in Fig. 2, the projecting channeled portions of the connector strips form, together with the web, a wide channel facing toward the panels and in which the panel elements are seated. In the upper portion of Fig. 2 there is illustrated a filler panel extending from the panel unit to the adjoining wall. This filler panel is a box-like structure comprising the side plates 40, a connector strip 30 and the U-shaped guide strip 41. The side plates 40 are telescoped into the U-shaped strip 41. The connector strip 30 and the guide strip 41 are interconnected by a tie-rod 43. This panel fills the space between the standard panel unit and the wall and is variable in width according to the exigencies of each 20 installation. Between the filler panel and the other partition wall against which the partition abuts at right angles is shown a panel which may comprise a window frame or a solid panel. The stiles of the casement are seated between the outer channels 30" of the connector strips 30. The web of member 44 is recessed to form a seat for the window pane or panel 45 which may be secured in place by putty or by any other suitable means. Preferably it is removably fastened by special clips 45a, but as this method of glazing forms the subject matter of another and copending application, it will not be further described herein.

25 In the event that it is desired to install a door near a corner, as shown at 47, Fig. 2, clearance space for the swing of the door must be provided to avoid damaging an adjacent panel. This construction as shown comprises a short spacer panel element 50 made up of two side plates 50' and two edge connector strips 30 secured together by a tie-rod 50". The panel element 50 is shown as attached on one side to an adjoining panel unit on one side and to an adjoining door unit on the other side by means of the diagonal struts 32. The door jamb is formed similarly to the window casement by inserting a special channel-shaped member 51 into a standard edge strip 30. It is securely held therein by an extra separator plate 52 and screws or bolts 53.

30 Fig. 3 shows a panel section abutting two other similar panels. Diagonal struts 54 join the upright 55 of the abutting panel to the uprights of the other two panels. It also shows additional fastening means of the window stiles to the uprights by screws 56.

The choice of a corner construction such as illustrated in Fig. 4 or one such as is illustrated in Fig. 5, depends upon the available space and other conditions. The standard or preferred construction is that of Fig. 5, while Fig. 4 calls for an extra box-shaped corner member comprising two rectangularly bent plates 57 and 58.

5 As Figs. 8 and 9 show, the rails of the glazed panel partitions are formed according to the same principle hereinbefore explained, using substantially channel-shaped members with fluted or corrugated webs and resiliently bent legs to be sprung over or into interlocking flanges of adjoining members, as 59 and 60.

10 The partition walls below the glazed panels are preferably formed of two sheet metal plates 61, 61, spaced apart and braced at top and bottom by channels 62 and 63 which may be welded or otherwise fastened to the side plates.

15 At the base intermediate the floor anchors a 20 mop strip 64 is shown which is substantially H-shaped in cross section, made of one continuous plate bent in the middle portion like an inverted channel, the legs being rebent and continued upwardly to form narrow troughs on the outside 25 of the inverted channel. The terminals of the rebent legs are ledged inwardly and folded downward. It will be seen from a close inspection of the base in Fig. 8 that a vertical plumb taken from the inner edges 65 of this ledge will strike the bottom of the trough, leaving just enough clearance with the leg of the inverted channel to insert a metal plate of the standard thickness of which the partition members are constructed. The space between the lower part of the metal 30 panel 61 of the partition and the base portion, which may vary with the unevenness of the floor, is covered by plate members 66, which, while rigidly seated within the base, will overlap the metal plates 61 in a telescopic fashion, thus 35 40 equalizing uneven heights. The lower portion of member 66 is recessed at 67 to form a seat on the ledge, and the recessed continuation of the member 66, entering the clearance space described above, is rabbeted at a suitable height to form a 45 resilient interlocking engagement with the inside terminal edge of the base 64 as shown at 68. These plate members 66, it will be observed, are so designed and assembled as to be easily removable, after complete erection of the structure 50 for purposes of the installation of electrical wires and the like. The connector strips suitably attached to the panels, are supported on the floor at a uniform level by special plates 69 which 55 compensate for any inequality of the floor by special means illustrated in Figs. 17, 18 and 19. These plates may be fastened to the floor in any suitable manner, such as by lag screws or anchor bolts 70. The plate itself has the shape of a U or large channel portion facing upwardly. 60 The web 69a rests on the floor and is provided with a slotted hole 71 for the anchor bolt. The legs 69b extend upwardly and are each provided with a pair of slots 72 and a pair of lateral ears or projections 73. The lower extremities of the 65 connector strips, or rather their grooved wings 30", are suitably slotted out, so that they straddle over these projections. The latter serve a double function. Beside holding the connector strips in alignment against lateral displacement, they 70 enter the grooved wings of the H-shaped base of the adjacent partition panel 64, as indicated in Fig. 8, and by their lower edge hold the same down to the floor. The slots 72 serve to hold in place the shim plates 74 which are inserted to 75

compensate for any unevenness of the floor which might prevent horizontal alignment of the panels. These shim plates are narrow rectangular pieces having projecting tongues 74' on either end which enter the slots 72. The uprights 30 5 rest upon these shim plates.

The base of the cover plates 36 (Figs. 2 and 8) may be provided with a base or mop board 36a welded or fastened to it in any suitable manner.

10 The panels may be secured to the connector strips by means of tongues (not shown) on the ends of the panels, which tongues may be passed through apertures in the connector strips as indicated at 95 in Fig. 16, and fastening keys may be 15 passed through the tongues.

It remains to describe the cornice construction and the means whereby the cornice is secured to the top of the partitions. The cornice member comprises a substantially hollow channel 26 20 made of sheet metal bent and rebent in any desired ornamental formation. At places where two lengths of cornice abut, an inner sleeve or fishplate 80 covers the seam. (See Fig. 8.) This sleeve closely follows the inner contour of the 25 cornice and is retained in position by the overturned top edges 26a of the cornice. To interiorly reinforce the cornice, it is provided with a suitable number of spanner plates 81. (See Figs. 12—14.) These plates are shaped to fit the inner contour 30 of the cornice, as illustrated in Fig. 12, and they are provided with slots 82 having an enlargement at 83 for the reception of a tie-rod 88, (Fig. 14). Two other circular apertures 84 are provided through which electric cables, telephone wires 35 and the like may be run. Into the top edge of the spanners are cut two recesses 85a and 85b in which the filler plates 86, made of composition board or the like, may be seated, if desired. These recesses are preferably cut on a slant and 40 wider than the thickness of the filler plates, so that the latter may be easily slid into them in an inclined position and then righted and locked into a vertical position as Fig. 12 indicates. The filler plates may be attached to the ceiling by any suitable 45 means, such for instance, as by a nailing strip 87.

The spanners 81 have a bottom flange 81' which forms a slightly obtuse angle with the main plate. As the top corners 89a and 89b are retained in 50 position by the bent over top edges 26a of the cornice and are just long enough to prevent their assuming a vertical position, it will be evident that when two spanners face each other, as in Fig. 14, for instance when two lengths of cornice abut, 55 they can be drawn by a tie-rod 88 into a rigid frictional engagement with the inner walls of the cornice, the spanner plates being wedged tightly between the channel web 26b and the bent over edges 26a of the cornice. Furthermore, there are 60 other locking means between the spanners and the cornice as well, as between the latter and the partition walls underneath. A series of cross-shaped apertures 90 are punched through the bottom 65 26b of the cornice at say about five inches between centers. A pair of oppositely positioned tongues 91 are incompletely punched out from the bottom 81' of the spanner so that they are still integral with the flange when bent downwardly, as shown in Figs. 12 and 13. Obviously, 70 by placing the spanner first over the middle of the cross-shaped hole and sliding it toward one end, these tongues can be inserted through the wider middle portion of the hole 90 and slipped underneath the edges of the longitudinal extensions, thus interlocking the cornice plate with 75

the spanners. This spanner connection may be employed in any desired combination, over the connector strips, as shown in Fig. 14, or across a cornice joint, etc.

The connection between the cornice and the 5 partition walls is made according to the same principle. Rectangular or oval shaped strips 92 are provided from which tongues 93 are partly pushed out and bent upwardly, as shown in Fig. 10, in a similar manner as that described above. 10 By inserting these strips 92 through the hole 90 so that the member 92 engages the inturned flanges of members 94 or 95, then driving member 92 into the elongated arms of hole 90, the 15 tongues 93 will engage the top of base of the cornice, thereby centering and fastening the engaging members.

It is, however, possible and entirely within the scope of our invention to attach the partition wall and cornices to the ceiling in a different way 20 by following the same principles which were used for the interconnection of the separate panel units to each other and the formation of hollow spaces between them. This construction is shown in detail in Fig. 20. The top 107 of the 25 partition wall is interconnected with a nailing strip 108 fastened to the ceiling in a manner analogous to the previously described interconnection between the units. The cornices 109 in 30 this case take the place of the pilaster plates 36 and are likewise resiliently seated upon the extant wings 110 of the horizontal strut holders 111 which correspond to the previously mentioned connector strips 30. The construction is 35 shown as applied to partitions of wood or composition material. However, it can obviously be also employed in connection with metallic partition units as above described. The interior of the cornices may also be filled with sound deadening material.

The base construction also shows a modification. Where the channel 112 or 112a, in which the panel units are seated, meet as at 113, they are coupled together by a fishplate 114 which on the longitudinal sides is recessed so as to properly keep the base channels separated, as shown 45 in Fig. 22. A bolt hole 115 is provided in the center of the fishplate for anchoring the same to the floor, as illustrated in Fig. 20.

While the foregoing description and the drawings illustrate certain embodiments of our invention, it is to be understood that other combinations and modifications are possible without deviating from the principles explained, and the invention is therefore not to be construed as limited to the details shown and described, but is to be interpreted in the light of the appended claims.

We claim:—

1. In partition wall construction panel units 60 having a plurality of socket members on their end faces and means for interconnecting adjacent panel units to each other comprising a plurality of swinging strut rods having off-set 65 ends of different lengths adapted to engage the socket members of the respective panel units.

2. In wall construction comprising a plurality of interchangeable wall panel units, means for securing the units together in edge to edge, 70 spaced apart, open relationship comprising two parallel rows of sockets on the vertical edges of each unit, strut members diagonally interconnecting the sockets of the respective adjoining units, and finish pilasters resiliently engaging the 75

end edges of adjoining units to cover the opening therebetween.

3. In wall construction comprising a plurality of interchangeable panel units, the combination 5 of means for interconnecting the units in spaced apart relationship comprising a plurality of sockets on the edges of adjoining units, a plurality of strut members diagonally engaging the sockets on the edges of the respective units to form a 10 truss-like connection, and finish pilasters resiliently engaging the end edges of adjoining units to cover the space therebetween.

4. In wall construction panel units provided on their vertical edges with metallic strips, sockets 15 formed on the outer faces of said strips, and means for interconnecting adjacent units comprising strut rods having offset ends of different length adapted to be seated swingingly in said sockets.

20 5. In partition wall construction, panel units provided on their vertical edge faces with metallic strips shaped on their inner faces to fit over the panels, a plurality of sockets struck out upon the outer faces of said strips, means for inter- 25 connecting adjacent panel units in spaced apart relationship comprising a plurality of pairs of struts adapted to seat in the sockets of the respective panels in diagonally disposed relationship, and finish pilasters resiliently engaging the 30 strips of adjoining units to cover the space therebetween.

6. In partition wall construction, a connector strip substantially channel-shaped, adapted on the open side of the channel to be connected to 35 an adjoining panel unit and provided on its outer web portion with sockets and means to combine the connector strips with a similar strip in parallel juxtaposition, said means comprising a plurality of staple-shaped strut rods adapted to be 40 seated in diagonally disposed relationship in said sockets of the respective connector strips.

7. In partition wall construction, panel units having connector strips, said strips being provided with two rows of socket members on the 45 edges facing adjoining panel units, said rows being parallel to each other and the sockets of the respective panel units facing each other in opposite pairs, and connecting means to combine said strips, said means comprising a plurality of 50 diagonally disposed staple-shaped struts adapted to be seated in said sockets, the struts crossing each other diagonally in pairs.

8. In partition wall construction, panel units each having two connector strips of substantial- 55 ly channel-shaped cross-section, the legs of said channels being doubled over to form narrow inverted channels, each pair of leg channels facing the leg channels of the connector strips on opposite panel units, a pilaster plate adapted to 60 cover the open space between the opposed connector strips, said pilasters being of substantially channel-shaped cross-section with longitudinally fluted legs adapted to resiliently engage the inverted leg channels of the connector strips, 65 and a floor plate comprising a U shaped pedestal with lateral vertical lugs engaging said narrow inverted channels of the connector strip.

9. In partition wall construction the combina- 70 tion with spaced apart panel units having con-

nectors strips and means for interconnecting opposed connector strips; of a floor plate adapted to support said connector strips adjustably, said floor plates comprising a U-shaped pedestal with lateral vertical lugs over which the connector strips, provided with suitable slots, are straddled and held against lateral displacement, a plurality of shim plates for supporting the connector strips adjustably and means integral with the pedestal to hold the shim plates in position, sub- 10 stantially as described.

10. In wall construction; panel units comprising side plate members, metallic connector strips constituting end framing for the plate members, the connector strips having a pair of longitudinal 15 parallel channels on their edges and a pair of longitudinal grooves on their webs adjacent to and parallel with the pair of channels, the channels and grooves cooperating to form seats for the side plate members, sockets formed on the webs 20 of the connector strips by retroverting portions of the grooves, and tie-rods connecting the connector strips.

11. In partition wall construction, two panel units in straight alignment and a third panel unit adjoining the first two at their point of joindure and at an angle thereto, means for interconnecting the respective panel units, said means comprising vertical edge connector strips on each panel unit and a plurality of sockets on the faces 30 of each of the connector strips, a plurality of strut rods, certain of which interconnect respectively the sockets of the two aligned panel units, and certain of which interconnect respectively the 35 sockets of the connector strips of the two aligned panel units and the connector strip of the right angularly disposed panel unit.

12. In partition wall construction, panel units in right angular corner juxtaposition, means for interconnecting said panel units, said means comprising vertical edge connector strips on each of the angularly disposed panel units, a vertical connector strip element opposite the end of one of the panel units, a plurality of sockets on the faces 40 of each of the connector strips and of the connector strip element, and a plurality of strut rods, certain of which interconnect respectively the 45 sockets in the vertical connector strips of the angularly disposed panel units, certain of which interconnect respectively the sockets of the connector strips of one of the vertical edge panel units and the connector strip element and certain of which respectively interconnect the sockets of the other of the vertical edge panel units and the connector strip element.

13. In wall construction, panel units having on their vertical edge faces metallic strips shaped to fit over the edges of the panels, said strips being provided with a plurality of sockets on the faces thereof which engage the end edges of the panels, 60 and means for interconnecting the panel units to form a wall, said means each comprising a pair of separately formed, staple-shaped struts adapted to be seated independently in said sockets in diagonally disposed relationship and acting in 65 complementary, opposed relation to each other when in place.

ALVIN C. GODDARD.
RAYMOND P. LE VINESS.
